UNITED STATES PATENT OFFICE.

HENRY C. HOLTHOFF, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

WATER-JACKET.

1,279,696.

Specification of Letters Patent. Patented Sept. 24, 1918.

Application filed September 2, 1916. Serial No. 118,599.

To all whom it may concern:

Be it known that I, HENRY C. HOLTHOFF, a citizen of the United States, residing at Milwaukee, in the county of Milwaukee and 5 State of Wisconsin, have invented a certain new and useful Improvement in Water-Jackets, of which the following is a specification.

This invention relates to improvements in 10 the construction of water jackets for cupola, blast and similar furnaces, and has particular relation to improvements in stay-bolts for such water jackets.

An object of the invention is to provide 15 a water jacket for cupola, blast and similar furnaces, which is simple and durable in construction and efficient in operation. One of the more specific objects is to provide a simple and efficient stay-bolt for water jackets. A further specific object is to provide means for effectively cooling the inside or fire sheet of a water jacket at the portions thereof to which the stay-bolts are attached.

25 It has heretofore been proposed in the construction of water jackets, to provide a stay-bolt having one end welded directly to the inside or fire sheet and having its opposite end passed through an opening in the 30 outside sheet and riveted or otherwise detachably secured to the outside sheet. It has also been proposed to provide a construction in which the stay-bolt is permanently secured by welding its ends to both 35 the inside and outside sheets. Another proposed construction of the prior art is to provide aligned openings in the two sheets and to pass the stay-bolt through these openings, riveting or otherwise securing the 40 outer end of the stay-bolt to the outside sheet and welding the inner end thereof to the inside sheet, the opening in the inside sheet adjacent the welded end of the bolt being subsequently closed by means of a 45 welded plug.

In order to avoid perforating or otherwise weakening the fire sheet at the points of attachment of the stay-bolt thereto, and also in order to permit ready attachment and removal of the bolt, it has been proposed to 50 weld or otherwise firmly secure a boss to the fire sheet and to detachably secure the stay-bolt to the boss, the opposite end of the bolt being fastened to the outside sheet by any 55 suitable means. This construction has the

advantage of maintaining the fire sheet imperforate and of uniform thickness at the portion thereof to which the stay-bolt is attached, and also permits ready attachment and removal of the bolt. The construction 60 last referred to forms the subject of an application Serial No. 28,793, filed May 14, 1915.

The present invention relates to an improvement in the device disclosed in the said 65 application, and consists primarily in providing means for effectively cooling the inside or fire sheet at the portions thereof to which the bolt supporting bosses are secured. This result is accomplished by forming passages through the bosses adjacent the inner ends of the stay-bolts through which passages fluid in the jacket may circulate.

A clear conception of several embodiments of the invention may be had by referring to the drawing accompanying and forming a part of this specification in which like reference characters designate the same or similar parts in the various views. 70 75

Figure 1 is a section through a fragment of a water jacket showing one form of stay-bolt.

Fig. 2 is a transverse section through the stay-bolt disclosed in Fig. 1 showing a fragment of the fire sheet, the section being taken along the line II-II of Fig. 1 looking in the direction of the arrow. 85

Fig. 3 is a section through a fragment of a water jacket showing another form of stay-bolt. 90

Fig. 4 is a transverse section through the stay-bolt disclosed in Fig. 3 showing a fragment of the fire sheet, the section being taken along the line IV-IV of Fig. 3 looking in the direction of the arrow. 95

The ordinary form of water jacket for cupola, blast and similar furnaces comprises essentially a pair of spaced parallel sheets having a cooling water chamber formed between them. The inside or fire sheet 1 is usually constructed of somewhat heavier material than that used for the outside sheet 2. In order to prevent collapse of the inside and outside sheets of the jacket, it is desirable to tie the two sheets 1, 2, firmly to each other at various portions of the jacket. For this purpose stay-bolts are ordinarily employed, these stay-bolts being distributed at various points throughout the jacket. 100 105 110

Referring specifically to Figs. 1 and 2, the inside or fire sheet 1 has a projecting element or boss 6 secured thereto preferably by welding. The boss 6 is provided with a through passage 13 adjacent the fire sheet 1, this passage communicating at its ends with the interior of the jacket. The boss 6 is also provided with a threaded socket extending transversely of the through passage 10 13. A stay-bolt 3 having a threaded end 12 of reduced diameter, is secured to the boss 6 by insertion of the threaded end 12 into the socket of the boss 6. The outer end of the stay-bolt 3 passes through an opening in the outside sheet 2, and is also screw threaded and of reduced diameter. A nut 11 which engages the threaded outer end of the bolt 3 clamps the outside sheet 2 firmly between the shoulder formed on the stay-bolt 3 by the reduction 15 20 in diameter of the end thereof, and a pair of washers 9, 10. The washer 9 is preferably formed of asbestos, while the washer 10 is formed of ordinary material. With this construction of stay-bolt 3 it will be noted that 25 the sheets 1, 2, are effectively prevented from spreading by the screw thread engagement of the ends of the bolt 3 with the boss 6 and nut 11, respectively, and from approaching each other by the shoulders formed by the 30 reduction in the diameters of the ends of the bolt.

Referring specifically to Figs. 3 and 4, the inside or fire sheet 1 has a projecting element or boss 7 secured thereto preferably 35 by welding. The boss 7 is provided with a through passage 14 adjacent the fire sheet 1, this passage communicating at its ends with the interior of the jacket. The boss 7 is also provided with a recess or slot 15. A stay-bolt 4 having a headed end 8 is inserted within the slot 15 so that the headed end 8 lies within the passage 14. The outer end of the stay-bolt 4 passes through an opening in the outside sheet 2 and is provided with screw threads. A bushing or sleeve 5 surrounds the portion of the stay-bolt 4 intermediate the boss 7 and outside sheet 2, the ends of this sleeve abutting the adjacent elements. A nut 11 engages the 45 threaded end of the stay-bolt 4 and clamps the bushing 5 between the boss 7 and outside sheet 2, this nut also clamping the outside sheet 2 between the sleeve 5 and a pair of washers 9, 10. The washer 9 is preferably 50 formed of asbestos, while the washer 10 is formed of ordinary material. With this construction of stay-bolt 4 it will be noted that

the sheets 1, 2, are effectively prevented from spreading by the engagement of the headed end 8 with the inner surface of the boss 7 60 and the engagement of the nut 11 with the threaded outer end of the bolt. Inward collapse of the sheets 1, 2, is prevented by the sleeve 5.

It will be noted that in each of the constructions of stay-bolt disclosed, the bolt may be readily applied without perforating or otherwise weakening the fire sheet 1 adjacent the bolt, thereby eliminating leaks at the point of attachment of the bolt to this 70 sheet. The stay-bolts may also be readily removed from the jacket, thereby permitting renewal in case of breakage of these bolts. By providing through passages 13, 14, in the elements or bosses 6, 7, the portions of 75 the fire sheet 1 adjacent the points of attachment of the stay-bolts to this sheet are, by circulation of the fluid in the jacket through these passages automatically maintained sufficiently cool to prevent burning of the sheet 80 at these portions.

It should be understood that it is not desired to be limited to the exact details of construction shown and described, for obvious modifications within the scope of the 85 appended claims will occur to a person skilled in the art.

It is claimed and desired to secure by Letters Patent,—

1. In combination, a fire sheet, an outside 90 sheet, an element secured to one of said sheets at an imperforate portion thereof, said element having a passage therethrough adjacent said sheet, a stay-bolt secured to said element, and means for securing said 95 stay-bolt to the other of said sheets.

2. In combination, a fire sheet, an outside sheet, an element secured to said fire sheet at an imperforate portion thereof, said element having a passage therethrough adjacent 100 said sheet, a stay-bolt secured to said element, and means for securing said stay-bolt to said outside sheet.

3. In combination, a fire sheet, an outside sheet, an element secured to said fire sheet 105 at a portion of said sheet which is imperforate and of uniform thickness, said element having a passage therethrough adjacent said sheet, a stay-bolt secured to said element, and means for securing said stay-bolt to said 110 outside sheet.

In testimony whereof, the signature of the inventor is affixed hereto.

HENRY C. HOLTHOFF.
